UNITED STATES PATENT OFFICE.

JOSEPH KRELL, OF BERLIN-PANKOW, GERMANY.

PRINTING MACHINE.

Application filed February 13, 1923. Serial No. 618,828.

To all whom it may concern:

Be it known that I, JOSEPH KRELL, residing at 16 Breitestrasse, Berlin-Pankow, Germany, have invented certain new and useful 5 Improvements in Printing Machines, of which the following is a specification.

This invention relates to printing or addressing machines and more particularly to machines of the kind described in U. S. Patent No. 1,532,890 in which printing plates are moved in succession into a printing position and during their movement control an impression device so as to cause any desired printing plates to pass on without producing an impression on the paper band. In this known machine blank spaces are left on the paper whenever a printing plate is prevented from producing its impression and the object of the present invention is to 15 prevent the occurrence of such blank spaces. This object is accomplished by providing a feed mechanism that only shifts on the paper or list whenever a printing plate has actually produced an impression. To this end the driving rod that actuates the automatic feed mechanism is not directly connected as hitherto to the movable impression lever, but intermediate links are arranged between the impression lever and the said 20 driving rod or thrust-rod, and these intermediate links are controlled by the levers that move the impression pad into its operative position in such a manner that feed motion is imparted to the paper feed mechanism not at each actuation of the impression lever, but only whenever the impression pad is moved into its operative position during the actuation of the impression lever, i. e., only when the impression pad causes a printing plate to make its impression on the paper band or list.

As the movements of the rod for driving the paper feed mechanism can only be adjusted within narrow limits by means of the 25 parts mounted on the impression lever, further means are provided in accordance with the invention which enable the motions of the driving rod to be increased so as to obtain practically any desired spacing between successive impressions on the paper band or list. Other features of the invention will appear hereinafter in the specification and claims.

The drawing illustrates the parts of an 30 addressing machine according to the invention which are deemed necessary for the un-

derstanding of the same, the other parts being omitted.

Fig. 1 is a sectional elevation of a machine 60 in its normal position,

Fig. 2 a plan view, and

Figs. 3 and 4 are sectional elevations corresponding to Fig. 1, the impression lever in both of these figures being shown in its lowered position, and Fig. 3 showing the position of the lever when a printing plate is skipped over, while Fig. 4 shows the position of the lever when the printing plate makes an impression on the paper.

Figs. 5 and 6 are elevations of details.

The general features of the novel addressing machine are similar to those of the machine described in the U. S. application referred to above. The machine comprises a table *a* with a raceway *a'* in which the printing plates *b* travel. The impression lever *2* is shaped in the form of an elbow and has a two-armed lever *z* pivotally mounted upon it. There is a frictional engagement at the pivot 1 between the lever *z* and the impression lever so that when the latter is swung round the lever *z* participates in the swinging movement, unless prevented from doing so by a catch as will be presently described. The lower end of the two-armed lever *z* cooperates with a hook or catch *u* forming the end of a two-part lever *r*, *s* loaded at the opposite end by a weight *t*. Whenever a printing plate is to be caused to make an impression on the paper band fed 80 through the machine an electro-magnet *n* is energized and this results in the rising of the catch *u* and in its engaging with the bottom end of the lever *z* as shown in Fig. 4. Linked to the upper end of the lever *z* is a set of levers 3, 4, 5, 6, 7, the lever 4, 5 being pivoted at 8 on the impression lever 2. The top end of the lever 7 is connected to a shaft 9 journalled in the head of the impression lever. A cam 15 may be mounted on, 100 or associated with, the shaft 9, and this cam may be adapted to push the impression pad 16 downwardly from the head of the impression lever, the extent to which the pad 16 is moved away from, or out of, the head depending on the position into which the shaft 9 is turned. An impression will be made on the paper by the printing plate *b* in the printing position only when the impression pad has been moved out of the position 105 shown in Fig. 1 into the position shown in Fig. 4 as a result of the rotation of the roll 110

- 15 or cam in the head of the impression lever 2. This impression pad has been described and claimed per se in U. S. Patent 1,436,981.
- 5 A feature of the invention comprises a two-armed lever 18, 19 pivoted at 17 to the impression lever 2. The upper arm 18 of the lever is connected by a draftrod 20 with the upper end of the lever z . Linked to the 10 lower arm 19 is a thrust-rod 21 whose other end is connected to the step-by-step list shifting device or feed mechanism for the purpose of actuating the same. To enable the points of engagement between the rods 20, 21 and the lever 18 to be shifted more or less from the center of rotation 17 the shafts of the bolts of the rods 20, 21 are arranged in slots in the lever 18 so that they can be 15 fixed at various distances from the pivot 17.
- 20 The device for shifting the printed list or paper band 22 across the path or raceway of the printing plate b and over the printing plates consists of two side rails 23, 24 fixed at a certain distance apart and between 25 which a guide plate 25 is adapted to slide. The guide rail 24 is channelled in the direction of its length to receive a rack or ratchet bar 26 adapted to reciprocate in the channelled rail 24 and provided with a bracket 27 which protrudes through an opening in the bottom of the guide rail 24. Attached to this bracket 27 is a short drawrod 28 pivoted to the triangular lever 29 which in turn is pivoted on a bolt 30 carried by a bracket 31 30 that is fixed to the guide rail 24. The rocker arm 29 is linked to the end of the thrust-rod 21 whose head 32 can be attached at various distances from the pivot 30 by means of the holes 33 in the rocker plate 29. When the 35 thrust-rod 21 is moved in the direction of the arrow 34 the rocker plate 29 is swung in the direction of the arrow 35, this resulting in a displacement of the ratchet bar 26 in the direction of the arrow 36. When the rod 40 45 21 is moved in the opposite direction the ratchet bar 26 is displaced in the direction opposite to that indicated by the arrow 36. The extent of each movement of the ratchet bar 26 will be different according to the 50 55 point at which the thrust-rod 21 is attached to the rocker plate 29, the same amount of travel of the rod 21 producing a greater displacement of the bar 26 the nearer its point of attachment is to the pivot 30.
- Above the ratchet bar 26 is a detent 37 60 65 mounted on the guide plate 25. This detent is pivoted on a bracket 38 and kept pressed downward into the teeth of the ratchet bar 26 by a leaf spring 39. Therefore, whenever the ratchet bar 26 is shifted in the direction of the arrow 36, the guide plate 25 is carried along to the same extent in the direction of the arrow 36, while movements of the ratchet bar in the opposite direction 70 75 80 85 90 95 100 105 110 115 120 125 130 do not affect the guide plate 25 because the

ratchet bar slips past the detent 37 lifting it out of each tooth and leaving the guide plate 25 in the position into which it had been moved by the forward stroke of the bar 26. Also mounted on the guide plate 70 75 80 85 90 95 100 105 110 115 120 125 130 135 140 145 150 155 160 165 170 175 180 185 190 195 200 205 210 215 220 225 230 235 240 245 250 255 260 265 270 275 280 105

ratchet bar is displaced in the opposite direction to the arrow 36. If the amount of motion imparted to the ratchet bar 26 is to be increased, it is only necessary to shift the 5 point of engagement 32 of the thrust-rod 21 nearer to the pivot 30 of the rocker plate 29. When after the printing plate has printed an impression and after the ratchet bar 26 has been shifted in the opposite direction to the arrow 36 through a distance of at least one tooth, the impression lever 10 returns from the position shown in Fig. 4 into the position shown in Fig. 1, the thrust rod 21 is also moved back into its initial 15 position, because the lever 2 will have been released during the return movement of the impression lever in the manner described in the aforesaid application and will again rotate with the impression lever 2 round the pivot 1. This return motion of the thrust rod 21 in the direction of the arrow 34 results in the ratchet bar 26 also moving back in the direction of the arrow 36 and during this movement the pawl 37 imparts a feed 20 motion to the guide plate 25 and to the paper band or list 22, the extent of this feed motion corresponding to the distance between two impressions on the paper. The spaces between the impressions will therefore all 25 be equal, the list or paper band remaining stationary or having no feed motion imparted to it whenever the impression lever 2 is lowered without the printing plate producing an impression on the paper.

35 I claim:—

1. In a machine of the kind described, a printing plate, an impression pad, means for feeding paper between said plate and said pad, auxiliary means for completing the 40 printing movement upon a partial printing movement of said plate and said pad, and means controlled in conjunction with said last named means for actuating said feeding means.

45 2. In a machine of the kind described, a printing plate, an impression pad, means for feeding paper between said plate and said pad, auxiliary means for completing the movement and performing a printing action 50 upon a partial movement of the pad toward said plate, and means controlled in conjunction with said auxiliary means for actuating said feeding means.

55 3. In a machine of the kind described, a printing plate, an impression member, means for feeding paper between said plate and said member, an impression pad on said impression member and movable relative thereto, and means for actuating said feeding means 60 on a relative movement between said pad and said impression member.

65 4. In a machine of the kind described, a printing member, an impression member for cooperating therewith, means for feeding paper between said members, off of said

members being adapted to execute a normally incomplete printing movement, auxiliary means for completing such a movement and means controlled in conjunction with said auxiliary means for actuating said feeding 70 means.

5. In a device of the kind described, a printing plate, an impression lever, an impression pad on said impression lever and adapted to be moved relative thereto, a lever 75 pivoted on said impression lever and adapted to move therewith, connecting mechanism between said pivoted lever and said impression pad, means for arresting said pivoted lever during a movement of the impression 80 lever whereby said impression pad is moved relative to the impression lever, and paper feeding means operated upon said relative movement.

6. In a device of the kind described, a 85 printing plate, an impression lever, an impression pad on said impression lever and adapted to be moved relative thereto, a lever pivoted on said impression lever, means whereby on a relative movement between 90 said pivoted lever said impression lever said impression pad is moved relative to said impression lever, and paper feeding means operated upon said relative movement.

7. In a device of the kind described, a 95 printing plate, an impression lever, an impression pad on said impression lever and adapted to be moved relative thereto, means for feeding paper between said plate and said pad, a lever pivoted on said impression lever and adapted to move therewith, connecting means between said pivoted lever, said impression pad, and said feeding means, and means for arresting said pivoted lever during a movement of said impression 105 lever whereby said impression pad and said feeding device are actuated.

8. In a machine of the kind described, the combination of printing plates, a paper feed device for shifting paper across the printing plates, a movable impression lever, an impression pad carried by the impression lever and movable relatively thereto and adapted when thus relatively moved to press the paper against a printing plate, an impression 110 pad actuating mechanism associated with the impression lever, and a link between the impression pad actuating mechanism and the paper feed device whereby the latter is actuated only upon actuation of the 115 impression pad.

9. In a machine of the kind described, the combination of printing plates, a paper feed device for shifting paper across the printing plates, a movable impression lever, an impression pad carried by the impression lever and movable relatively thereto and adapted when thus relatively moved to press the paper against a printing plate, a pivoted 125 lever in frictional engagement with the im- 130

- pression lever and adapted to participate in its movements, means for arresting the pivoted lever while the impression lever is moved, an impression pad mover, links 5 mounted on the impression lever and connecting the said pivoted lever to the impression pad mover and adapted to operate the latter when the pivoted lever is arrested, a two-armed lever pivoted on the impression lever and having a long arm and a short arm, a draw-rod connecting the long arm to the pivoted lever, and a thrust-rod connecting the short arm to the paper feed device, the said arms being adapted to transmit a feed motion through the thrust-rod to the feed device whenever the impression lever is moved and the pivoted arm is arrested.
10. In a machine of the kind described, 20 the combination of printing plates, a paper feed device for shifting paper across the printing plates, a movable impression lever, an impression pad carried by the impression lever and movable relatively thereto and adapted when thus relatively moved to press the paper against a printing plate, a 25 pivoted lever in frictional engagement with the impression lever and adapted to participate in its movements, means for arresting the pivoted lever while the impression lever is moved, an impression pad mover, links 30 mounted on the impression lever and connecting the said pivoted lever to the impression pad mover and adapted to operate the latter when the pivoted lever is arrested, a two-armed lever pivoted on the impression lever and having a long arm and a short arm, a draw-rod connecting the long arm to the pivoted lever, a pivoted rocker arm 35 with points of connection at various distances from its pivot, a link between said point of connection and the said ratchet bar, and a thrust rod connecting the said short arm to the rocker arm, the said long and short arms being adapted to transmit a feed motion through the thrust rod, rocker arm, 40 link and ratchet bar to the paper feed device whenever the impression lever is moved and the pivoted arm is arrested, and the extent of the feed motion depending on what said point of connection the said link is connected to.
11. In a machine of the kind described, the combination of printing plates, a paper feed device for shifting paper across the printing plates, a ratchet bar for actuating the paper feed device, a movable impression lever, an impression pad carried by the impression lever and movable relatively thereto and adapted when thus relatively moved to press the paper against a printing plate, a 50 pivoted lever in frictional engagement with the impression lever and adapted to participate in its movements, means for arresting the pivoted lever while the impression lever is moved, an impression pad mover, links 55 mounted on the impression lever and connecting the said pivoted lever to the impression pad mover and adapted to operate the latter when the pivoted lever is arrested, a two-armed lever pivoted on the impression 60 lever and having a long arm and a short arm, a draw-rod connecting the long arm to the pivoted lever, a pivoted rocker arm with points of connection at various distances from its pivot, a link between said 65 point of connection and the said ratchet bar, and a thrust rod connecting the said short arm to the rocker arm, the said long and short arms being adapted to transmit a feed motion through the thrust rod, rocker arm, 70 link and ratchet bar to the paper feed device whenever the impression lever is moved and the pivoted arm is arrested, and the extent of the feed motion depending on what said point of connection the said link is connected 75 to.
- In testimony whereof I affix my signature.
- JOSEPH KRELL.
